UNITED STATES PATENT OFFICE

102,591

DESIGN FOR A FRAMED EMBLEM OR SIMILAR ARTICLE

Viola T. Howard, Saylesville, R. I., assignor to
Swank Products, Inc., Attleboro, Mass., a cor-
poration of Delaware

Application August 27, 1936, Serial No. 64,590

Term of patent 7 years

To all whom it may concern:

Be it known that I, Viola T. Howard, a citizen of the United States, residing at Saylesville, in the county of Providence and State of Rhode Island, have invented a new, original, and ornamental Design for a Framed Emblem or Similar Article, of which the following is a specification, reference being had to the accompanying drawing, forming a part thereof.

The figure of the drawing is an isometric view of the framed emblem or similar article showing my new design, the particular characters shown in dotted lines on the middle panel being merely illustrative.

The dominant feature of the invention consists in the three forwardly curved panels of contrasting colors enclosed in a frame of the form shown.

The back of the article is plain to the extent of being devoid of ornamental characteristics.

I claim:

The ornamental design for a framed emblem or similar article substantially as shown and described.

VIOLA T. HOWARD.
